DRAFT AND BUFFING GEAR

Charles E. Dath, Chicago, Ill., assignor to W. H. Miner, Inc., Chicago, Ill., a corporation of Delaware

Application January 27, 1933, Serial No. 653,784

4 Claims. (Cl. 213—9)

This invention relates to improvements in draft and buffing gears especially adapted for mine cars.

The main object of this invention is to provide a simple, efficient and durable combined draft and buffing gear for mine cars which may be quickly assembled and applied to the car.

A more specific object of this invention is to provide a gear of the character described in the preceding paragraph, comprising draft and buffing springs, a buffing head, a draft yoke and an enclosing housing, wherein simple and efficient means is employed for holding the buffing head assembled with the housing and limiting the outward movement of the buffing head and also serving while being applied in assembling the parts to place the springs under the required initial compression.

Other objects of the invention will more clearly appear from the description and claims hereinafter following.

In the drawing, forming a part of this specification, Figure 1 is a part top plan and part horizontal sectional view of my improved gear, illustrating the same as applied to one end of a mine car. Figure 2 is a longitudinal vertical sectional view, partly broken away, corresponding to the line 2—2 of Figure 1. Figure 3 is a longitudinal vertical sectional view, corresponding substantially to the line 3—3 of Figure 1. Figures 4 and 5 are transverse vertical sectional views, partly broken away, corresponding respectively to the lines 4—4 and 5—5 of Figure 1.

In said drawing, 10 indicates one of the end sill members of a mine car, said end sill being shown as forming an integral part of the car underframe structure, which, in the particular car illustrated, is in the form of a single casting.

My improved combined draft and buffing gear comprises broadly, a housing A; a buffing head B; a yoke C; a pair of combined retaining and stop keys D—D; a pair of springs E—E; and a coupling pin G.

As shown in the drawing, the housing A is preferably formed as an integral part of the end sill 45 10, which end sill is also a part of the underframe casting of the car. However, as will be understood by those skilled in the art, my improvements are not limited to the housing being thus formed, and it is within my invention to employ 50 a separate end sill member, or form the housing as a separate member which is fixed to the end of the car. The housing A has a rearwardly extending section of reduced width and height, which forms a spring cage portion. The housing 55 is defined by spaced side walls 12—12, spaced

top and bottom walls 13 and 14, and a vertical back wall 15. The housing is open at the front end and has the spring cage portion 11 thereof disposed rearwardly of the vertical front web 16 of the end sill member 10. As clearly shown in 60 Figures 1 and 2, the top, bottom and side walls of the housing are inwardly offset to produce the reduced spring cage portion thereof. As illustrated most clearly in Figures 1, 2 and 3, the bottom wall of the housing has a forwardly extending section 17, which projects beyond the front edge of the top wall 13 and forms a ledge for properly supporting the sliding buffing head B. The side walls 12—12 have inturned, vertically 65 extending flanges 18—18 at their forward ends, 70 which form abutment shoulders for the combined retaining and stop keys D—D.

The buffing head B has the rear end portion thereof telescoped within the housing and is slidably supported on the bottom wall 14 of the 75 housing. The head B is defined by spaced vertical side walls 19—19, horizontal top and bottom walls 20—20, a pair of spaced, longitudinally extending walls 21—21 between the top and bottom walls and relatively short vertical front end walls 80 22—22 connecting the top and bottom walls and with the walls 21—21. The walls 22—22 are curved as shown in Figure 1, thereby presenting transversely rounded buffing surfaces which are 85 in vertical alignment. The spaces between the walls 21—21 and the top and bottom walls 20—20, respectively, define guide ways for the arms of the yoke C, as hereinafter more fully described. The walls 21—21 are shorter than the walls 19—19 and 20—20, and converge inwardly towards each 90 other, as clearly shown in Figure 3. The space between the walls 21—21 defines an opening 24, adapted to accommodate the usual coupling link 23. The walls 21—21 are connected at their inner ends by a vertical web 25, which forms an abutment for the front ends of the springs E—E. The web 25, as well as the walls 21—21, are formed integral with the side walls 19—19 and the latter are cut away between the walls 21—21 so that the opening 24 is continuous from side to 100 side of the buffing head, thereby accommodating the link 23 when the latter is in the dotted line position of Figure 1. The walls 20—20 and 21—21 are provided with vertically aligned, longitudinally extending slots 26—26 and 26—26, 105 adapted to receive the coupling pin G. The inner surfaces of the side walls 19—19 are spaced apart the same distance as the side walls of the spring cage portion 11 of the housing A, and are in alignment with the last named walls. The buffing head 110

is further provided with lateral flanges 27-27 at its inner end, which are formed integral with the side walls 19-19. The flanges 27-27 are of such a width that they pass freely between the flanges 18-18 of the housing A, to permit telescoping of the buffering head within the open end of the housing in assembling the parts of the gear. The web 25 is preferably provided with a central opening 28, which gives clearance for the rear end of the coupling link 23 and thereby permits the maximum required rearward displacement of the link.

The yoke C has spaced top and bottom arms 29-29 and a vertical rear end section 30 connecting the arms. The section 30 forms an abutment 15 for the rear ends of the springs E-E, and is of greater width than the arms 29-29 so as to provide ample bearing surface for the pair of springs as clearly shown in Figure 5. The arms 29-29 are guided respectively between the walls 20-21 and 20-21 of the buffering head B. At the forward ends, the arms 29-29 are preferably thickened as indicated at 31-31, and these thickened portions are provided with aligned vertical openings 32-32, which register with the slots 26-26 of the buffering head B. The openings 32-32 receive the pin G, which substantially fits these openings.

The springs E-E are disposed within the yoke and have their opposite ends bearing respectively on the abutment wall 25 of the buffering head and the vertical rear end section 30 of the yoke.

The combined retaining and stop keys D-D are in the form of elongated, relatively heavy, flat bars of substantially rectangular cross-section. Each key has the bottom end thereof beveled, as clearly shown in Figures 2 and 3, and said beveled end is split, as illustrated in Figures 4 and 5, to permit spreading of the end of the key to prevent accidental removal of same. At the upper end, each key has a laterally projecting portion forming head 33. The keys D-D are disposed at opposite sides of the buffering head, in back of the flanges 18-18 of the housing A, and extend through vertically aligned openings 34-34 and 34-34 in the top and bottom walls of the housing. Each key D is of such a width as to occupy the space between the walls 12 and 19, at the corresponding sides of the housing A and buffering head B. As shown most clearly in Figure 1, the keys D-D are disposed in front of the flanges 27-27 of the buffering head and are overlapped by the latter so that outward movement of the buffering head is limited by engagement between these flanges and keys D-D. The keys D-D, in addition to holding parts assembled and limiting outward movement of the buffering head, serve to hold the springs under initial compression.

In assembling my improved combined draft and buffering gear, the springs E-E are first placed within the yoke C, the buffering head B is then engaged over the outer ends of the arms 29-29 of the yoke, and the yoke C with the buffering head are applied to the housing A by telescoping the rear end portion of the buffering head B within the enlarged front section of the housing A. When the parts have been thus far assembled, the flanges 27-27 of the buffering head B are located a slight distance inwardly of the flanges 18-18 of the housing A. The keys D-D are next applied by inserting the same through the upper openings 34-34 of the housing A, and driving the same between the flanges 18-18 and 27-27 of the housing A and buffering head B. Due to the lower ends of the keys D-D being beveled, the buffering head B will be forced inwardly into the housing

A by wedging action of the beveled ends against the flanges 27-27 of the buffering head. When completely applied, the split lower end portions of the keys D-D are spread apart, as clearly shown in Figures 4 and 5, thereby locking the keys 80 in position. As will be evident, when the keys have been completely applied, the buffering head B will be in such a position that the springs E-E are under compression.

In a buffering action, the head B will be forced inwardly, thereby compressing the springs E-E against the vertical rear end section 30 of the yoke C, while the latter is held against rearward movement by engagement with the vertical rear wall 15 of the housing A. Inward movement of the buffering head B will be limited by engagement with the wall 16 of the housing. In a draft action, when a pulling force is applied to the yoke C through the coupling link 23 and pin G, the yoke will be moved outwardly of the housing, 90 thereby compressing the springs E-E against the abutment wall 25 of the buffering head B. At this time, the buffering head B is stationary, due to engagement of the flanges 27-27 with the keys D-D, which keys in turn are held against 100 outward movement by engagement with the flanges 18-18 of the housing A. The draft movement of the yoke C is limited by the pin G engaging the outer end walls of the slots 26-26 of the buffering head B.

I have herein shown and described what I now consider the preferred manner of carrying out my invention, but the same is merely illustrative and I contemplate all changes and modifications that come within the scope of the claims appended 110 hereto.

I claim:

1. In a combined draft and buffering gear for a car, the combination with a housing having side walls provided with inturned flanges at the forward ends; of a buffering head slidable between the side walls of the housing, said head having laterally outwardly directed flanges at opposite sides; a pair of retaining keys having engagement with the flanges of the housing and buffering head for limiting outward movement of said head, said keys being tapered to wedge said buffering head inwardly of the housing when said keys are driven into position between the flanges of the housing and buffering head when the parts are being assembled; and spring means yieldingly opposing movement of the buffering head inwardly of the housing.

2. In a combined draft and buffering gear for a car, the combination with a housing open at the forward end and having inturned flanges at said end; of a buffering head telescoped within the housing, said head having laterally outwardly projecting flanges at said inner end, the outer edges of said last named flanges terminating laterally inwardly of the inner edges of said first named flanges; vertically disposed keys at opposite sides of the buffering head, fixed to the housing and overlapping the flanges of both the housing and buffering head; a yoke within the housing; means within the yoke yieldingly opposing relative movement of the yoke and buffering head; and a coupling pin extending through said buffering head and yoke and limiting outward movement of the yoke with respect to the buffering head.

3. In a combined draft and buffering gear for a car, the combination with a supporting casing of a yoke extending into said casing, said yoke having top and bottom arms; a buffering head telescoped within the casing and enclosing said yoke arms, said head having top and bottom

guideways receiving said arms, said head also having a coupling link receiving opening between said arms; means yieldingly opposing relative movement of the yoke and head; and a coupling pin extending through said buffering head and the arms of the yoke, said pin intersecting the coupling link receiving opening of the buffering head.

4. In a combined draft and buffering gear for a car, the combination with a housing having interior, rear abutment faces and spaced side walls, said side walls having inturned flanges at the outer ends; of a buffering head having a transverse front wall presenting an outer buffering surface, said head being slidably between the side walls of said housing, said buffering head having outturned flanges at opposite sides thereof, said outturned flanges engaging said rear abutment faces

of the housing to limit rearward movement of the buffering head; vertically disposed keys at opposite sides of the buffering head, each of said keys being disposed between one of the flanges of the buffering head and one of the flanges of the housing and overlapping both of said flanges, said keys limiting outward movement of the buffering head; cushioning means yieldingly resisting movement of the buffering head inwardly of the housing, the front end of said cushioning means bearing on the front wall of the buffering head; a yoke having a transverse rear end section bearing on the rear end of said cushioning means; and means for connecting the yoke to a coupling link, said means including a coupling pin extending through the front end of the yoke.
